Bert N. Parmenter, Inventor;
By Parkinson & Lane, Atty.

relation with respect to each other, whereby an inclined ventilating opening of variable size is provided between the cross rails and communicating with both the inside and the outside atmosphere.

The upper sash comprises a cross rail 19, side rails 20, a pane 21 held in by putty or the like 22, and an upper cross rail 23 having a cross section approximating a right angled triangle 10 similar to the cross rail 14 and having its longer side projected from the sash in a vertical plane, the hypotenuse of the triangle constituting an inclined or beveled surface 25. A fixed cross rail portion 24 also is provided, similar in cross section to the fixed rail 15 having the short side of the triangle abutting the lintel 4 and with its longer side projecting downwardly in a vertical plane, the hypotenuse 26 intersecting the vertical side to provide a free edge 32. The beveled 20 surfaces or hypotenuses 25 and 26 and the projected edges 31 and 32 are in precisely the same relation as the beveled surfaces 16 and 17 and free edges 29 and 30, and cooperate in the same manner. Duplicate description of the functions of 25 these parts is therefore considered unnecessary.

It will be apparent that when the lower sash is raised as from the dotted line position to the full line position shown thereof in Fig. 1 of the drawings, there is provided an inclined louver 30 space 27 for the passage of ventilating air as indicated by the arrows on the drawings. Likewise, when the upper sash is lowered as from the dotted line position to the full line position shown thereof in Fig. 1 of the drawings, there is provided an 35 inclined louver space 28 for the passage of air as indicated by the arrows on the drawings. When the sashes are in closed position, the usual locking means (not shown) on rails 10 and 19 will so cause a wedging action at the faces 16 and 17, and 40 faces 25 and 26 as to make the sashes press tightly against the guide rail 6 and thus prevent rattling and the like.

By providing the louver spaces 27 and 28 on a bias or incline, rain is shed and prevented from 45 entering the room. It is preferable not to raise the lower sash with the lower edge 29 of the rail portion 14 substantially above the level of the upper edge 30 of the rail portion 15, and likewise not to lower the upper sash with the upper edge 50 31 of the rail portion 23 substantially below the level of the lower edge 32 of the rail portion 24.

To increase the extent of the louver spaces and still have the advantage of rain shedding and the like, the invention comprehends the provision of 55 auxiliary louver means.

As for example, in Figs. 2 and 3 is shown an auxiliary louver 33 having its ends 34 slidably mounted in inclined grooves or channels 35 provided in the sides 1 of the window frame. This 60 louver may be a sheet of glass, or metal, or wood, or fibre, or composition, etc., and it is slidable in the grooves with sufficient friction so as to remain in any given slid position. The grooves are in alignment with the louver surface 17 so that 65 the louver 33 may act substantially as an extension of the surface 17 and yet may be slid down over the surface 17 (see dotted line position thereof in Fig. 2) whereby when the sash is in closed position the surface 16 will seat and 70 seal with the upper face of the louver 33. When the louver 33 is in raised position as shown in full lines in Fig. 2, its upper edge 36 is substantially higher than the upper edge 30 of the rail part 15, so that the lower sash may be raised 75 higher with the lower edge 29 of the rail portion

14 substantially on the level with the upper edge 36 of the louver 33. This provides for an increased louver space 27' for permitting greater ventilation of air as shown by the arrows in Fig. 2 of the drawings.

While the above structure has been described in connection with the lower part of the window and the lower sash, the same means may be provided in the upper part of the window in connection with the upper sash except in inverted 10 position.

Another type of auxiliary louver may be used as shown in Figs. 4, 5, and 6, with the auxiliary louver of Figs. 2 and 3 as shown in Figs. 5 and 6, or without the same as shown in Fig. 4. In this case is provided an auxiliary louver 37 which may be of sheet metal or any other material as desired. The ends 38 of this louver are fast with the lower ends 39 of channel shaped bars 40 each of which is slidably mounted in a channel, which may be an extension of the rope channel, provided in each side rail of the sash. The inner face 41 of the bar 40 is provided with a slot 42 in which projects a pin 43 secured in the side rail 11 of the sash and in the back of the channel in the 25 sash. Likewise in the upper part of the window is a like louver 44 the ends of which are fixed to the lower ends of channel shaped bars 45 each of which is slidably mounted in the usual rope channel or rope channel prolonged provided in each side rail of the upper sash. The inner face 30 of this bar has a slot 46 in which projects a pin 47 secured to the end of rail portion 24 and in the back of the rope channel thereof.

Normally when the window sashes are closed 35 the louver 37 is seated between the faces 16 and 17 of the rail portions 14 and 15 and the louver 44 is seated between the faces 25 and 26 of the rail portions 23 and 24. When the lower sash is raised the louver 37 first remains seated on the face 17 until the pins 43 carried by the sash reach the upper ends of the slots 42 in the bars 40 after which the bars 40 and the louver 37 are carried upward and attain the position shown in full lines in Fig. 4 of the drawings. The lower edge 48 of the louver 37 is about on the level with the upper edge 30 of the rail portion 15, and the lower edge 29 of the rail portion 14 is about on the level with the upper edge 49 of the louver 37. When lowering the sash, the louver 37 first descends with the sash until the louver seats on the face 17, and then the pins 43 descend in the slots 42 until the face 16 seats on the louver 37. By the above described means, an increased louver space is obtained.

When lowering the upper sash, the louver 44 first descends with the rail portion 23 until the upper end of the slot 46 contacts the pin 47 fixed in the sash part 24, then the sash continues to descend leaving the louver suspended as shown in full lines in Fig. 4 of the drawings. The upper edge 31 of the rail portion 23 is about on the same level as the lower edge 50 of the louver 44 and the upper edge 51 of the louver 44 is about on the same level as the lower edge 32 of the rail portion 24, thus giving an increased louver space.

If it be desired to increase the louver space, the louver 33 may be used, the structure being the same as disclosed in connection with Figs. 2 and 3 of the drawings. In this case when the louver sash is raised the lower edge 48 of the louver 37 is about on the level with the upper edge 36 of the louver 33, thus giving further louver space.

In Figs. 7, 8 and 10 are shown further forms 75

of auxiliary louvers for increasing the louver spaces. As shown in Fig. 7, a louver of sheet material, such as metal, comprises a base part 52 secured by screws 53 or other suitable securing elements to the rail portion 14, a resilient bend 54, louver or visor portion 55, and bead 56. The louver portion 55 extends substantially in alignment with the face 16 of the rail portion 14 so as to form a louver extension therefor. In this case when not using an auxiliary louver at the base, that is, with rail portion 15, the window sash may be raised with the bead 56 about level with the edge 30 of the rail portion 15. When the sash is closed, the louver part 55 engages the ledge 2 to over-lie it as shown in dotted lines in Fig. 7, the bend 54 acting as a resilient member for this purpose. When the sash is raised the louver portion 55 is restored in position to form an extension of the face 16 of rail portion 14.

20 However, to further increase the louver space, a louver 57 of sheet material, such as metal, may be provided, this louver having its ends 58 slidably mounted in grooves 59 provided in the sides 1 of the window frame and in alignment with the face 17 of the rail portion 15. The upper edge of the louver 57 preferably has a bead 60. When the louver 57 is in its raised position as shown in full lines in Fig. 7, the sash may be so raised as to bring the bead 56 of the louver 55 about level with the bead 60 of the louver 57. When the louver 57 is lowered it seats on the face 17 of rail portion 15 and when the sash is closed the face 16 of the rail portion 14 seats on the louver 57, as shown in dotted lines in Fig. 7. 25 It will be noted that the bead 60 of the louver 57 is shorter (Fig. 10) than the louver 57 itself, so that the ends 61 of the bead 60 will be flush with the inner surfaces of the stops 5 at the loci of the grooves 59.

40 In Fig. 8, is shown a louver 62 having a portion 63 secured as by screws or other suitable securing elements 64 to the rail portion 24 and a visor portion 65 in alignment with the face 26 of the rail portion 24 to form an extension of the face 26. The lower edge portion of the louver is provided with a bead 66.

When the upper sash is lowered it may be lowered to the extent of having the edge portion 31 of the rail portion 23 about level with the 50 bead 66, thus giving an increased louver space between the rail portions 23 and 24.

In the forms shown in Figs. 4, 5 and 6, if it be desired to set the auxiliary louver 37, a locking means may be provided comprising a head 67 having a handle 68, and a screw shank 69 having an end portion adapted to lock or set the slide bar 49 to hold it and the louver 37 from sliding down when the window is raised. A similar means may be provided for the louver 44 for the 60 upper sash when it is desired to prevent the louver 44 sliding down when the upper sash is lowered.

In Figs. 11 and 12 is shown an auxiliary louver means similar to that shown in Figs. 4 and 5 but having an additional louver 70 secured to the upper ends of channel shaped bars 71 each slidably in a guide 72 and a passage 73 provided in the ledge 2, the guide 72 being secured in any 70 suitable way via a flange 72'. The inner wall 75 of the bar 71 has a slot 74 in which extends a pin 75 secured to a fixed part in the guide channel as at the end of the rail portion 15. Between the lower ends 76 of the bars 71 and the lower 75 ends 77 of the guide 72 are located springs 78

adapted to raise the bars 71 and the louver 70 connected to them into the position shown in Fig. 11. When the sash is closed, as shown in Fig. 12, the louver 70 seats on the face 17 of the rail portion 15, while the louver 37 seats on the louver 70, and the face 16 of the rail portion 14 seats on the louver 37. When the sash is raised, the springs 78 lift the bars 71 and louver 70, as also louver 37, until the lower ends of the slots 74 contact the pins 75 whereby the louver 70 stops in spaced relation above the face 17. The continued raising of the sash causes the face 16 to rise from louver 37, the latter remaining on louver 70 until the upper ends of the slots 42 hit pins 43 at which instant the louver 37 is picked up and raised from the louver 70, the face 16 being spaced from the louver 37. In this way three louver spaces are provided thus increasing the total louver space as clearly shown on the drawings. This is illustrative of providing as many louvers as desired in the sash space.

Having thus disclosed a few illustrative embodiments of my invention, it is to be understood that the invention is not limited thereto but comprehends other constructions, arrangements of parts, details, features and the like without departing from the spirit of the invention.

Having thus disclosed the invention, I claim:

1. A ventilator window comprising a window frame provided with stiles, an end portion and a fixed cross rail, said cross rail being of a cross section approximating a right angled triangle with one side longer than the other, the shorter side of the triangle abutting said end portion and the longer side of the triangle projecting from said end portion in a vertical plane, the hypotenuse of the triangle constituting an inclined surface intersecting the projected end of said long side to provide a free edge, a window sash mounted in said frame and including a cross rail movable therewith, said last mentioned cross rail having a cross section approximating a right angled triangle of similar shape and dimensions as those of the fixed cross piece, and having its long side projected vertically from the sash, the hypotenuse of the triangle constituting an inclined surface intersecting the projected end of said long side so as to provide a free edge, the respective hypotenuses lying parallel with each other, with one longitudinal edge of each at the inside of the sash and the other longitudinal edge of each at the outside of the sash, said sash and its cross rail being slidably mounted in said window frame to maintain said free edges in relatively adjustable overlapped relation with respect to each other, whereby a ventilating opening of variable size is provided between the cross rails, a sheet-like auxiliary louver, and means for adjustably supporting said louver within the space between said cross rails and in a position parallel with the beveled faces thereof.

2. A ventilator window comprising a window frame provided with a stationary cross rail, a window sash mounted in said frame and including a cross rail movable therewith, said cross rails being respectively provided with biased louver surfaces, the louver surface of each cross rail being complementary to the louver surface of the other cross rail, said biased surfaces being so related with respect to each other as to provide overlapped portions which will be in abutted wedged relation while the sash is in completely closed position, each of said biased surfaces having a free edge, said free edges being projected in opposite directions, said sash and its cross

- 5 rail being slidably mounted in said frame to maintain said free edges of the cross rails in relatively adjustable overlapped relation with respect to each other, whereby an inclined ventilating opening of variable size is provided between the cross rails, said opening having one end terminating inside of the window and the other end terminating outside of said window, an auxiliary louver located between the louver surfaces of the 10 respective cross rails in such manner as to lie approximately parallel with said surfaces, and means for moving said auxiliary louver in a vertical plane while maintained in its inclined position.
- 15 3. A ventilator window comprising a window frame provided with a stationary cross rail, a window sash mounted in said frame and including a cross rail movable therewith, said cross rails being respectively provided with biased louver surfaces, the louver surface of each cross rail being complementary to the louver surface of the other cross rail, said biased surfaces being so related with respect to each other as to provide overlapped portions which will be in abutted 20 wedged relation while the sash is in completely closed position, each of said biased surfaces having a free edge, said free edges being projected in opposite directions, said sash and its cross rail being slidably mounted in said frame to maintain 25 said free edges of the cross rails in relatively adjustable overlapped relation with respect to each other, whereby an inclined ventilating opening of variable size is provided between the cross rails, said opening having one end terminating inside of the window and the other end terminating outside of said window, an auxiliary louver movably mounted in a position between the louver surfaces of the respective cross rails, and means 30 operated by movement of said sash for moving said auxiliary louver to a predetermined position with respect to the first mentioned louver surfaces.
4. A ventilator window comprising a window frame provided with a stationary cross rail, a window sash mounted in said frame and including a cross rail movable therewith, said cross rails being respectively provided with biased louver surfaces, the louver surface of each cross rail being complementary to the louver surface of the other cross rail, said biased surfaces being so related with respect to each other as to provide overlapped portions which will be in abutted 45 wedged relation while the sash is in completely closed position, each of said biased surfaces having a free edge, said free edges being projected in opposite directions, said sash and its cross rail being slidably mounted in said frame to maintain 50 said free edges of the cross rails in relatively adjustable overlapped relation with respect to each other, whereby an inclined ventilating opening of variable size is provided between the cross rails, said opening having one end terminating inside of the window and the other end terminating outside of said window, support bars 55 slidably mounted in said window frame, one or more auxiliary louvers carried by said support bars and interposed between the louver surfaces of said cross pieces, and means connecting said support bars with said window sash in such manner that said support bars are moved by said sash by movement of the latter in either direction.
- 70 5. A ventilator window comprising a window frame provided with a stationary cross rail, a window sash mounted in said frame and includ-
- 5 ing a cross rail movable therewith, said cross rails being respectively provided with biased louver surfaces, the louver surface of each cross rail being complementary to the louver surface of the other cross rail, said biased surfaces being so related with respect to each other as to provide overlapped portions which will be in abutted wedged relation while the sash is in completely closed position, each of said biased surfaces having a free edge, said free edges being projected in opposite directions, said sash and its cross rail being slidably mounted in said frame to maintain 10 said free edges of the cross rails in relatively adjustable overlapped relation with respect to each other, whereby an inclined ventilating opening of variable size is provided between the cross rails, said opening having one end terminating inside of the window and the other end terminating outside of said window, support bars 15 slidably mounted in said window frame, said bars having longitudinal slots therein, an auxiliary louver carried by said support bars and interposed between the respective louver surfaces of said cross rails, and pins carried by said sash and projected into said slots 20 whereby said support bars are moved by the sash during 25 slide movements thereof, said pins and said slots being so relatively constructed and arranged as to provide a limited movement of the sash in either direction before imparting 30 slide movement to said support bars.
6. A ventilator window comprising a window frame provided with a stationary cross rail, a window sash mounted in said frame and including a cross rail movable therewith, said cross rails being respectively provided with biased louver surfaces, the louver surface of each cross rail being complementary to the louver surface of the other cross rail, said biased surfaces being so related with respect to each other as to provide 35 overlapped portions which will be in abutted wedged relation while the sash is in completely closed position, each of said biased surfaces having a free edge, said free edges being projected in opposite directions, said sash and its cross rail being slidably mounted in said frame to maintain 40 said free edges of the cross rails in relatively adjustable overlapped relation with respect to each other, whereby an inclined ventilating opening of variable size is provided between the cross rails, said opening having one end terminating inside of the window and the other end terminating outside of said window, support bars 45 slidably mounted in said window frame, said bars having longitudinal slots therein, an auxiliary louver carried by said support bars and interposed between the respective louver surfaces of said cross rails, pins carried by said sash and projected into said slots 50 whereby said support bars are moved by the sash during slide movements thereof, said pins and said slots being so relatively constructed and arranged as to provide a limited movement of the sash in either direction before imparting slide movement to said support bars, and means for releasably holding said support bars in any position to which it may have been moved by said sash.
7. A ventilator window comprising a window frame provided with a stationary cross rail, a window sash mounted in said frame and including a cross rail movable therewith, said cross rails being respectively provided with biased louver surfaces, the louver surface of each cross rail being complementary to the louver surface of the 70

other cross rail, said biased surfaces being so related with respect to each other as to provide overlapped portions which will be in abutted wedged relation while the sash is in completely closed position, each of said biased surfaces having a free edge, said free edges being projected in opposite directions, said sash and its cross rail being slidably mounted in said frame to maintain said free edges of the cross rails in relatively adjustable overlapped relation with respect to each other, whereby an inclined ventilating opening of variable size is provided between the cross rails, said opening having one end terminating inside of the window and the other end terminating outside of said window, pairs of support bars slidably mounted in said window frame, a plurality of louvers, one secured to each support bar at positions between the louver surfaces of the latter, means for yieldably moving one set of support bars upwardly, means for limiting the upward movement of the last mentioned support bars, and means providing a lost motion connection between said sash and the other support bars.

8. A ventilator window comprising a window frame provided with a stationary cross rail, a window sash mounted in said frame and including a cross rail movable therewith, said cross rails being respectively provided with biased rail surfaces, the louver surface of each cross rail being complementary to the louver surface of the other cross rail, said biased surfaces being so related with respect to each other as to provide overlapped portions which will be in abutted wedged relation while the sash is in completely closed position, each of said biased surfaces having a free edge, said free edges being projected in opposite directions, said sash and its cross rail being slidably mounted in said frame to maintain said free edges of the cross rails in relatively adjustable overlapped relation with respect to each other, whereby an inclined ventilating opening of variable size is provided between the cross rails, said opening having one end terminating inside of the window and the other end terminating outside of said window, and auxiliary louvers carried by the respective rails in such manner as to lie parallel with each other and each having a louver portion arranged in alignment with the louver surface of its cross rail.

10. A ventilator window having a frame and a sash, said sash having a cross rail comprising portions parted on a bias with one of said portions fixed to the frame and the other of said portions being movable with the remainder of the sash so that as the sash is moved an inclined ventilating louver space is provided between said portions, an auxiliary louver, and means provided in said sash for movably supporting said auxiliary louver for movement in the space provided between said portions.

tive cross rails in such manner as to lie approximately parallel with such surfaces, means for moving said auxiliary louver in a vertical plane while maintained in its inclined position, and a second auxiliary louver secured to the cross rail of the said sash and projected outwardly therefrom in approximately the same plane as the louver surface thereof.

9. A ventilator window comprising a window frame provided with a stationary cross rail, a window sash mounted in said frame and including a cross rail movable therewith, said cross rails being respectively provided with biased louver surfaces, the louver surface of each cross rail being complementary to the louver surface of the other cross rail, said biased surfaces being so related with respect to each other as to provide overlapped portions which will be in abutted wedged relation while the sash is in completely closed position, each of said biased surfaces having a free edge, said free edges being projected in opposite directions, said sash and its cross rail being slidably mounted in said frame to maintain said free edges of the cross rails in relatively adjustable overlapped relation with respect to each other, whereby an inclined ventilating opening of variable size is provided between the cross rails, said opening having one end terminating inside of the window and the other end terminating outside of said window, and auxiliary louvers carried by the respective rails in such manner as to lie parallel with each other and each having a louver portion arranged in alignment with the louver surface of its cross rail.

10. A ventilator window having a frame and a sash, said sash having a cross rail comprising portions parted on a bias with one of said portions fixed to the frame and the other of said portions being movable with the remainder of the sash so that as the sash is moved an inclined ventilating louver space is provided between said portions, an auxiliary louver, and means provided in said sash for movably supporting said auxiliary louver for movement in the space provided between said portions.

BERT N. PARMENTER.
